UNITED STATES PATENT OFFICE

2,590,401

HAT HOLDER

Reed Druley Gordon, Detroit, Mich.

Application April 17, 1947, Serial No. 742,158

2 Claims. (Cl. 211—32)

1

This invention relates to improvements in devices for holding hats and the like, and more particularly to the provision of a hat holder which can be readily adjusted to accommodate hats of different sizes.

It is, therefore, an object of the invention to provide a hat holder of wire construction which occupies little space, and when not in use occupying no more space than the usual wire coat hanger.

A further object is to provide a hat holder which can be conveniently inserted in and removed from a hat by simply manipulating a cord to distort spring members forming a part of the holder.

A further object is to provide a hat holder which is simple in operation, capable of being manufactured at a low cost and having no parts to get out of order.

These and other objects are attained by the novel construction and arrangement of parts, hereinafter described and illustrated by the accompanying drawings, forming a part hereof, and in which:

Fig. 1 is a perspective view of the hat holder.
Fig. 2 is an elevational view of the device.

Fig. 3 is a view showing a hat positioned on the holder.

Referring to the drawings, the hat holder is shown to be formed of a unitary spring wire which is bent to form an upper cross bar 1 with inturned portions 2 substantially parallel to the bar 1. The bar 1 and the portions 2 are secured to a wall or other support by screws 3, bolts, or the like.

Extending down from the portions 2 are inclined portions 4, integral with outwardly extending portions 12, which are integral with short upturned sections 5, which are integral with downturned bowed sections 6 forming 40 hooks 13.

The lower ends of the bowed sections 6 are bent back to provide inwardly extending arms 14, the ends of which are curled to provide eyelets 7 through which pass a cord 8, the ends of which, as shown at 9, pass through and frictionally engage a clip 10, the lower ends of the cords 9 being attached to a tassel 11 below the clip 10.

In operation, a pull is exerted on the cords 50 9 to cause the portion 8 of the cord to draw the bowed members 6 together as shown in dotted lines in Fig. 1, to collapse the hat holder. The hat is then put on the holder and the cord released. The bowed sections and other sections 55

2

spring outwardly to engage the hat and hold it in shape.

By moving the clip 10 to different positions along the cord sections 9, the bowed sections 5 6 can be drawn in or allowed to expand to accommodate hats of different sizes. The hooks 13 are adapted to engage the upper edge of the sweat band of a hat to prevent accidental removal of the hat from the holder.

10 The device is obviously simple in construction and easy to manipulate. It can be manufactured at a low cost and has no parts to get out of order.

15 The above description is to be considered as illustrative and not limitative of the invention of which modifications can be made without departing from the scope of the invention as set forth in the appended claims.

The invention having been described, what is 20 claimed is:

1. A hat holder, comprising a spring wire form having a cross arm with inturned ends, said ends being below and in the same vertical plane as the cross arms, diverging inclined sections connected to the ends, outwardly extending horizontal parallel portions connected to the inclined sections, downwardly extending outwardly bowed sections connected to said outwardly extending portions, the lower ends of said bowed sections being bent back to provide inwardly extending parallel arms, the ends of said inwardly extending arms being curled to form eyelets, and a cord passing through said eyelets. 25

30 2. The structure set forth in claim 1 further characterized by said outwardly extending portions having short upturned sections connecting said portions to the downwardly extending bowed sections to provide hooks.

REED DRULEY GORDON.
